PULL TOY

Ronald J. Campanell, Blackwood, N.J., assignor to The Quaker Oats Company, Chicago, Ill.

Filed Dec. 10, 1973, Ser. No. 423,406

Term of patent 14 years

Int. Cl. D21—01

U.S. Cl. D34—15 D

FIG. 1

FIG. 2

FIG. 3

FIG. 1 is a front perspective view of a pull toy showing my new design;

FIG. 2 is a rear elevational view thereof; and

FIG. 3 is a bottom plan view thereof.

In FIGS. 2 and 3 the bellow member and the connecting tube have been omitted for ease of illustration only.

I claim:

The ornamental design for a pull toy, substantially as shown and described.
